UNITED STATES PATENT OFFICE

JEAN D. SEGUY, OF CHICAGO, ILLINOIS, ASSIGNOR TO UNIVERSAL OIL PRODUCTS COMPANY, OF CHICAGO, ILLINOIS, A CORPORATION OF SOUTH DAKOTA

TREATMENT OF HYDROCARBON OILS

Application filed January 10, 1929. Serial No. 331,436.

This invention relates to the treatment of hydrocarbon oils by heat for the production of light valuable distillates, by means of processes wherein cracking may take place either as a primary or secondary object. The feature of the invention may be applied, for instance, to a type of process, among others, where the oil is heated to elevated temperatures in a heating zone, such as a coil, then transferred to an enlarged zone where separation of vaporized from unvaporized products, with or without accompanying reaction, may occur; where the vapors may be removed from such enlarged zone, and thereafter subjected to dephlegmation and where the vapors remaining uncondensed after dephlegmation are condensed and collected, after separation from the so-called non-condensable gas, in the form of lighter distillates, motor fuels, or gasoline-like products. In such type of process, vapors condensed in the dephlegmator may or may not be returned to the process for further treatment and the unvaporized products separated in the enlarged zone may be removed therefrom without being returned to the heating zone.

In the operation of such processes, whether used principally for cracking or where cracking takes place as a secondary action, it has been proposed to maintain the heating coil and the enlarged zone under substantially the same superatmospheric pressure, and it has also been proposed to maintain the heating coil under superatmospheric pressure and the enlarged zone under a reduced pressure. It has also been proposed, particularly for so-called vapor phase cracking, to use relatively low superatmospheric or substantially atmospheric pressures on the entire process.

In these processes, the pressure maintained on the vapors produced while they are subjected to dephlegmation may be substantially the same as, or relatively lower, than that maintained on the enlarged reaction or separating zone, although still above atmospheric, or it may be substantially atmospheric pressure.

In order to condense the gasoline-like or lighter condensable materials and separate them from the non-condensable gases after

dephlegmation, it has been proposed, in some processes, to rectify this entire mixture of non-condensable gases and condensable vapors, including every fraction thereof from the lightest fractions to the heaviest ones entering into the composition of said non-condensable gas and gasoline-like or light distillate, said vaporous mixture entering the rectification zone at a temperature corresponding approximately to the boiling points of the heavier fractions of the mixture under the pressure used.

In other types of processes it has been proposed that this condensation and separation of the vapors and incondensable gases after dephlegmation be effected, first, by condensing the condensable materials and cooling the mixture to approximately atmospheric temperature, thereafter passing the materials remaining uncondensed and separated from the liquefied fractions to a rectifying or so-called vapor recovery zone.

The proposed types of processes just described have disadvantages when compared to some of the features of the process of the present invention. The process of the present invention, in some of its features, proposes to effect rectification or condensation of the gasoline-like or lighter liquefiable products, and their separation from the gases in such manner that substantially no, or comparatively little, gas will be withdrawn in solution in the liquefied fractions after separation has taken place. It also proposes that the rectification of non-condensable from condensable fractions, to sharply separate them into light liquid hydrocarbons and relatively dry gas, be effected on a mixture of the non-condensable gases produced and of only the lighter portions of the liquefiable gasoline or light vapors removed from the dephlegmating zone of the process.

It is to be understood that when reference is made to uncondensable or liquefiable materials, this is to be taken in relation with the state of these materials when at atmospheric pressure and ordinary temperatures.

Returning now to the various processes heretofore referred to, wherein the features of this invention may be used, and more

particularly to such processes where cracking is permitted to take place, as a primary purpose, it is generally recognized that the phenomena of cracking may be divided into 5 two phases—one, the so-called splitting reaction, whereby smaller molecules are formed, and the other, the so-called polymerizing reaction, forming larger molecules than those contained in the original oil, and producing, if carried too far, objectionable amounts of so-called sludge or coke, which are undesirable products of a cracking operation.

Owing to some of the features of this invention, the cracking reaction is so controlled 15 as to get a maximum amount of the so-called splitting phase of the reaction and a minimum amount of the so-called polymerizing phase; by this process of controlled pyrolysis I have found that the amount of coke or sludge formed can be reduced from a very 20 large amount to an amount which may be as small as one-fiftieth of the amount ordinarily formed if the reaction is not controlled 25 as herein described.

According to one of the methods of practicing this invention, I preferably control the degree of reaction obtained in the heating zone or coil, dependent upon the time element and temperature and pressures used, by inserting, on the end of the coil, a valve, by means of which I reduce the pressure from that used in the coil to a much lower pressure at precisely the right time, so that the 30 oil as delivered from the heating zone is reduced from its high pressure to a lower pressure, thereby cooling the oil by vaporization and checking the reaction at about the time at which the objectionable polymerizing 35 phase of the cracking reaction would begin; thereby substantially preventing the formation of undesirable coke and sludge. I have also found that, after having obtained in this manner a controlled pyrolysis of the hydrocarbons in the heating zone, it is necessary to control the rate of withdrawal from the 40 process of the heavier unvaporized liquid products which result from such controlled pyrolysis and which accumulate in the enlarged zone of reduced pressure. This rate of withdrawal will depend upon the degree of pyrolysis obtained in the heating zone, the 45 degree of reduction of pressure between the heating zone and the enlarged zone, the temperature maintained or obtained in the latter, and upon the maximum tolerance for the 50 formation of sludge and coke.

It may be necessary that in an apparatus used to carry out the invention, the rate of 55 withdrawal of the heavier liquid products from the enlarged zone be such that the level of such unvaporized products be maintained at a low point in said zone.

I have found that different oils require a 60 different combination of time, temperature in

the heating zone, pressure drop at the discharge of the heating zone, and rate of withdrawal to get the best results desired.

It will be understood that when the oil is passing from the heating zone through a valve to a zone kept at a much lower pressure than the heating zone, two cooling effects may be obtained. One of them is that due to the expansion of the heated mass on reduction from a high pressure to a low pressure which is known as the Joule-Thompson effect, and the other may be the cooling effect due to the passage of the oil from the heating zone to the zone into which the oil is discharged at a low pressure, which zone may not be heated by external means, and from which the products are rapidly withdrawn.

A modified method of operation may be carried out as follows:

I may treat the oil in the heating zone and the enlarged zone without the interposition of a valve between said zones, maintaining substantially the same pressure in both, which may be atmospheric pressure or above. In an operation of this character, I may obtain a controlled pyrolysis of the hydrocarbons by proper control of the temperature to which the oil is subjected in the heating zone, or the rate at which the oil passes through the apparatus, or the pressure maintained on the heating and enlarged zones, and the rate of withdrawal of the unvaporized liquid products separating in the enlarged zone, and by a proper balance between these factors.

In some instances, when producing liquid residues from the process, the proper balance may be indicated, when the desired yield of lighter products from the operation is being obtained, by the content of sludge in the unvaporized products removed from the enlarged zone. This content should be, in all instances, below the maximum allowed, which may be around 5% but preferably around 2%, based on the liquid products removed from said zone.

When comparing two operations carried out in the heating zone or coil and enlarged zone according to the alternative methods described, where every condition remains the same, except that in one operation the pressure is reduced at the end of the coil, while in the other it is not, the operation where the pressure is reduced at the end of the heating coil, because of the drop of temperature accompanying the pressure reduction, may permit of maintaining the unvaporized products in the enlarged zone a longer time than the other operation, before the same degree of polymerization is obtained.

Returning to the features of the invention which concern the treatment of the vapors and gases separated in the enlarged zone from the unvaporized products of reaction or distillation, this phase of the invention may be

carried out in processes where, as a result of the reduction of pressure between the heating zone and the enlarged zone, the following dephlegmation, separation, and recovery of 5 the lighter products are necessarily carried out at relatively low super-atmospheric or at substantially atmospheric pressure. This phase of the invention is also applicable to processes wherein the pressure on the heating 10 and enlarged zones is equalized and varies from substantially atmospheric to a high degree of superatmospheric pressure; the pressure on the dephlegmating and subsequent vapor treating zones may therefore 15 vary from substantially atmospheric to a high superatmospheric pressure; in such processes it may be desirable, however, to maintain the pressure on the said last named zones at a substantial atmospheric or a relatively 20 low super-atmospheric pressure, even if to do so it is necessary to reduce the pressure on the vapors leaving the enlarged zone, relative to the pressure used therein.

The dephlegmation or rectification of hydrocarbon vapors is easier and cheaper as the pressure used is lowered. At lower pressures it is possible to make sharper separation between condensed and uncondensed materials than at higher pressures, because the vapor 30 pressure curves of the constituents are farther apart at low than at high pressures.

It may also be advantageous to use low pressures for dephlegmation and rectification insofar as the cost of the material and operation 35 is concerned.

However, the use of relatively low superatmospheric or substantially atmospheric pressure on the dephlegmating, condensing and separating zones, employed in processes herein referred to, has some disadvantage when compared with processes where these operations are carried under higher pressure. This resides in the fact that when the non-condensable fractions are separated from the 45 liquefied fractions removed therewith after cooling to ordinary temperatures, the so-called non-condensable gases carry with them valuable lighter condensable hydrocarbons in a quantity which increases as the pressure under which the separation is effected decreases.

On the other hand, the liquefied portions separated from non-condensable gas, after cooling to ordinary temperatures, carry dissolved with them substantial quantities of 55 non-condensable gases; this quantity increases as the temperature of separation decreases, and as the pressure under which the separation is effected increases.

Some of the features of my process herein described, eliminate or substantially decrease the disadvantages of heretofore proposed processes independently of the pressure under which dephlegmation, condensation, and rectification are carried out.

65 The ease and efficiency with which rectifica-

tion processes may be carried out for sharp separation of two fractions depends primarily upon the difference between the boiling points of these two fractions under the conditions described. In a mixture of hydrocarbon vapors, the higher the boiling points of the fractions considered, the closer are the boiling points of the individual hydrocarbons which make up the fractions. For instance, in the lighter or low boiling point portions, generally called non-condensable gas, the difference between the boiling points of some of the constituents thereof may amount to approximately 35 degrees F. or more. As one considers a heavier or higher boiling fraction, the boiling points of the pure hydrocarbons constituting such fraction become closer together, and in heavier fractions having a boiling point range between, say, 400 and 450 degrees F., the difference between the boiling points of the pure hydrocarbons entering the composition of these fractions may only amount to a few degrees F.

I have found that it is unnecessary and wasteful on the efficiency and cost of the operation to include, in a rectification process for sharp separation of so-called non-condensable gas from gasoline-like products, the heavier fractions of the vapors which, after condensation, will enter in the composition of the gasoline-like or light liquid products from the process.

Therefore, according to one of the features of the invention, the mixture of non-condensable gases and vapors produced in the distillation and/or conversion of hydrocarbon oils may be removed from the dephlegmating zone of the process at such temperature under the pressure used, that their end point corresponds, for instance, approximately to the end point of gasoline-like or other light liquid products. This vaporous mixture is then subjected to partial condensation and cooling, under the pressure at which the dephlegmation was effected, or under a different pressure, down to a temperature above the prevailing atmospheric temperature. Such partial condensation and cooling is so controlled that only the heavier portions of the vaporous mixture are condensed, still leaving in vaporous form the incondensable gas and lighter vapors of the mixture. These condensed heavier fractions are removed from the process, and the remaining mixture of lighter condensable vapors and non-condensable gases is subjected to rectification for sharp separation of the liquefiable fractions from the non-condensable gases, the latter in the form of substantially dry gas. Said lighter liquefiable fractions condensed during rectification may thereafter be combined with or kept separate from the heavier vaporous fractions subjected previously to partial condensation, to form commercially useful prod-

ucts having the character of gasoline or other useful light hydrocarbon materials.

The object of this feature of the invention is to avoid the unnecessary rectification of the heavier fractions of the vapors removed from the dephlegmating zone, and, therefore, obtain considerable improvement over such processes heretofore referred to, which propose subjecting heavier and lighter vapors and gases together to rectification, and wherein in rectification of the heavier fractions decreases the efficiency and increases the cost of the operation without improving the separation of the liquefiable hydrocarbons from the so-called non-condensable gases.

The process of the invention also possesses considerable advantages over processes heretofore described where the vapors and non-condensable gases removed from the dephlegmation zone are cooled to a temperature approximating atmospheric before separation and rectification. In such processes, the liquefied vapors separated from the gas at ordinary temperatures carry non-condensable gases in solution out of the separation zone in an amount which, every condition remaining the same, depends upon the temperatures at which the separation is effected, and decreases rapidly as this temperature increases.

Therefore, the partial condensation and cooling of the gas and vapors down to a temperature substantially above atmospheric and the separation of the condensed heavier distillate from the remaining gas and vapors at that point, according to my invention, results in materially reducing the quantity of gas carried out by the distillate at that point, relative to the quantity carried out at ordinary temperatures. This advantage is due to the smaller quantity of fractional distillate removed at that point, and primarily to the decreased solubility of the gas in the distillate on account of the higher temperatures.

The invention, therefore, possesses advantages over processes where the vapors from the dephlegmation zone are cooled down to atmospheric temperature in that it decreases materially or substantially prevents a substantial amount of gas passing out of the system with the fractions condensed, and separated before rectification; this practically eliminates or substantially decreases the loss of light valuable fractions incurred by subsequent gas release or evaporation in separating or storage tanks, and decreases materially the cost of recovery of such light valuable fractions.

In short, some of the features of the process of the invention consist in fractionally condensing or dephlegmating hydrocarbon vapors to form a mixture of so-called non-condensable or fixed gas and condensable vapors having an end point approximately that of the useful product desired from the operation of the process, then taking this mixture

and partially condensing and cooling it to temperatures above the prevailing atmospheric temperature, to liquefy only the heavier fractions of the condensable vapors, separating these liquefied heavier fractions from the non-condensed fractions and then subjecting the non-condensed fractions, including non-condensable gas, to rectification for the separation of the lighter condensable fractions from the non-condensable gases in as dry a form as possible.

The removal, from the materials sent to rectification, of the heavier liquefiable fractions considerably improves the facility with which the rectification may be effected, at the same time decreasing the investment and the operating expenses required therefor.

Other features of the invention will be apparent from the following description of the process, and, for illustration, I have shown in the drawings attached, various forms of apparatus in which this invention may be carried out.

Fig. 1 shows a diagrammatic sketch, in no sense to scale, of an apparatus which may be utilized in carrying out the invention.

Fig. 2 shows a modified form of apparatus which may be used. This drawing is only diagrammatic and not to scale.

It is to be understood that whenever reference is made to boiling points, the figures given are the boiling points of the material when considered under atmospheric pressure.

Referring to Fig. 1, and to an illustration of an operation which may be carried out in the apparatus shown therein, the oil to be subjected to treatment may be drawn from storage tanks through pipe 1 and forced by means of pump 2 into feed line 3 from which it enters the heating coil 4. The heating coil 4 is positioned in a furnace 5 of any conventional type. The oil is heated in the coil to the temperature required for the treatment, and discharges therefrom through line 5', in which may be interposed valve 6, into an enlarged drum 7 in which separation of heavier unvaporized liquid residue from lighter vaporized products takes place. The unvaporized liquid residue may be withdrawn from drum 7 through residue drawoff line 8, controlled by valve 9 and directed to further treatment or to storage through line 10. The vapors separated in drum 7 may be removed therefrom through line 11 having valve 12 and directed to dephlegmating, fractionating, or rectifying zone 13, which is provided with any conventional means suitable for such operation. Cooling means at the upper portion of zone 13 and heating means at the bottom of said zone may be provided to effect a proper degree of dephlegmation desired through heat interchange with cooling and heating agents, in direct or indirect contact with the vapors undergoing dephlegmation. These temperature regulating agents may be

introduced or passed through lines 14 and 15, controlled by valves 16 and 17, or through any other suitable means. In addition, a portion of, or all of the raw oil to be treated may be charged to the dephlegmating zone 13 through line 18 by proper manipulation of valve 19 on said line and valve 20 on line 3.

Heavier portions of the vapors from the process are dephlegmated and condensed in dephlegmating zone 13, and this condensate, depending upon the purpose of the treatment, may be withdrawn from the dephlegmating zone 13 through line 21 and thence returned to the charging line 3 through line 22 in which may be interposed valve 23 and hot oil pump 24; or this condensate may be removed from the system and sent to storage or to treatment elsewhere through line 25 in which is interposed valve 26. Or, by suitable regulation of valves 23 and 26, any desired portion of this condensate may be withdrawn from the system while the other portion is returned to the heating tubes 4.

The vapors and gases remaining uncondensed in dephlegmation zone 13 may be removed from the top thereof through line 27 in which may be interposed valve 28, and may then be passed through condenser cooler 29 wherein they may be subjected to partial condensation and cooling, as heretofore described, in such manner that only the heavier portions of these vapors are liquefied while passing through said condenser. The mixture of heavier distillate and lighter uncondensed vapors and gases leaving the condenser 29 may discharge into hot separator 30. The condensed portion may be removed therefrom through line 31 in which are interposed valves 32 and 35, and sent to storage or further treatment. If desired, it may also receive additional cooling down to atmospheric temperature in cooler 33, positioned on a by-pass from line 31 and controlled by valves 34. This heavier distillate may afterwards be mixed with those fractions of the vapors separated in hot separator 30 which will be liquefied during rectification as will be hereafter described, and the mixture thus obtained may then be directed to treatment or to storage.

Returning to the lighter fractions of the vaporous products withdrawn from dephlegmator 13 which remain uncondensed after passage through partial condenser 29 and separation from the heavier distillate in the hot separator 30, they may be removed from the latter through line 36 in which is interposed valve 37. Line 36 may also be provided with a by-pass 38 in which may be interposed valves 39 and pump 40 which may be cut into the apparatus. This mixture of uncondensed lighter vapors and gases is thus directed to stabilizing or rectifying zone 41, which latter may be provided at the bottom and at the top, respectively, with suitable

well known heating or reboiling and cooling means such as illustrated at 42 and 43. There the uncondensed vapors and gases from the process are separated sharply into a condensed lighter distillate and substantially dry mixture of gaseous and unstable hydrocarbons. These may be withdrawn from the top of the stabilizing or rectifying column 41 through line 44, provided with valve 45. The condensed and rectified lighter distillate may be removed from the bottom of zone 41 through line 46, provided with valves 47 and 50 through which it may be directed to storage or further treatment separately; or such lighter rectified distillate by the use of branch 48, provided with valve 49, connecting discharge lines 31 and 46, may be mixed in suitable proportions with the heavier distillate resulting from the partial condensation in condenser cooler 29, and the mixture may then be directed to further treatment or to storage.

Now referring to Fig. 2, I have shown a modified form of apparatus which may be used in connection with oil treating apparatus such as shown in Fig. 1, but in lieu and place of the partial condensing and rectifying parts shown in Fig. 1.

In the use of this modified apparatus, the vapors remaining uncondensed in dephlegmating zone 13 may be removed from the top thereof through line 27 having valve 28 and may be passed into a rectifying zone 101 provided with upper cooling means 102 and lower heating means 103. There the temperature is so controlled that the condensable vapors and uncondensable gases, removed from dephlegmating zone 13 through line 27, may be partially condensed as heretofore described. The condensed heavier fractions may then be withdrawn from the bottom of rectifying zone 101 through line 104 having valves 105 and 120 and directed separately or in admixture with lighter materials to storage or further treatment with or without additional cooling down to ordinary temperatures. The uncondensable gas and lighter fractions from the vapors withdrawn from dephlegmating zone 13, and which have not been condensed in the rectifying zone 101 may pass out of the latter through upper drawoff 106 provided with valve 107 and with by-pass 108, controlled by valves 109, in which is interposed vapor pump 110. Through line 106, or through the by-pass 108, these uncondensed materials may pass into a stabilizing or rectifying zone 111 wherein sharp separation is effected between the lighter condensable material and the uncondensable gases. This rectifying zone 111 is provided with bottom heating means 112 and upper cooling means 113. The substantial dry uncondensable gases may be withdrawn from the top of stabilizing or rectifying zone 111 through line 113', having valve 114, and may be directed to further

treatment or storage, while the lighter condensed distillate may be withdrawn therefrom through line 115 having valves 116 and 117 whereby it may be directed separately to storage or further treatment; or by proper control of valves 117, 120 and of valve 119 on by-pass 118, such lighter material and the heavier condensate withdrawn from rectifying zone 101 may be mixed in suitable portions to form a mixture having the characteristics of motor fuel or other valuable light distillates, which may then be directed to further treatment or to storage.

Without further describing in detail other modified forms of apparatus which may be used to carry the features of this invention, I may mention that dephlegmating zone 13 of Figs. 1 and 2 may comprise one or more dephlegmators, or that the fractions which may be separated by condensation therein, to produce from the dephlegmating zone vapors having the desired end points, can be removed as one or more separate streams of varying characteristics. When the dephlegmating zone comprises for instance, two dephlegmators, the vapors from enlarged zone 7 will then be subjected to a series of dephlegmations. The condensate from the first dephlegmator may be returned to the heating coil for treatment, or removed separately and the vapors from said dephlegmator may pass through the second dephlegmator. In said second dephlegmator, the condensate produced therein may be separately evacuated to storage or subjected to treatment, and the vapors from said second dephlegmating zone may then pass to the rectification zone, including the step of partial condensation, shown at 29, 30 and 41 in Fig. 1 and at 101 and 111 in Fig. 2, for the vapors leaving dephlegmating zone 13 shown in said figures.

The operation of the processes described with the types of apparatus referred to herein is preferably so regulated that the vapors entering the partial condensing zone, such as zone 29 in Fig. 1 and zone 101 in Fig. 2 have an end boiling point corresponding nearly to the end boiling point of motor fuels or light distillates, such as gasoline.

As an illustration of a method for operating some features of this process, vapors and uncondensable gas entering the partial condensation or rectification zone through line 27 may be at such temperature, under the pressure used, that will give material having an end boiling point of about 420 to 440 degrees F. at atmospheric pressure. Then in partial condensation and separation zones 29 and 30 of Fig. 1, or in rectifying zone 101 of Fig. 2, this material may be subjected to partial condensation or rectification, at a temperature under the pressure used, such that the bulk of the material condensed and withdrawn through line 31 or through line

104 may begin to boil, at atmospheric pressure, at a temperature of 200 degrees F., more or less. The amount of material boiling below 200 degrees F. left in this heavier distillate will depend upon the sharpness of the separation obtained in this partial condensation or rectification step. In this manner, the material left uncondensed in separator 30 of Fig. 1 and in rectifier 101 of Fig. 2 may be composed of hydrocarbons, the bulk of which will have boiling points lower than approximately 200 degrees F., at atmospheric pressure. This uncondensed material is then passed into the stabilizing or rectifying zone 41 of Fig. 1 or 111 of Fig. 2, where the temperature is such that the material condensable at atmospheric pressure and ordinary temperatures is separated from the so-called uncondensable gases. The material condensed therein and withdrawn through pipes 46 or 115 will thus have an end point of approximately 200 degrees F. more or less. This lighter distillate may then be blended with the heavier distillate withdrawn through line 31 or line 104 in suitable proportions to constitute a gasoline-like motor fuel which may correspond to specification and which may have an end boiling point of about 437 degrees F.

In another method of carrying out the invention, these two streams of heavier and lighter distillates may be kept separate. The stream of heavier distillate having boiling points at atmospheric pressure between about 200 and 450 degrees F., as heretofore described may be kept separate and sold or utilized as naphtha or otherwise, while the stream of lighter distillate withdrawn from stabilizing zone 41 or 111 may be utilized by blending with suitable material for the manufacture of high grade aviation gasolines having end boiling points, at atmospheric pressure, of approximately 325 degrees F.

It is to be understood that the conditions heretofore given as illustrations are not to be understood as limiting the invention and that the temperatures at which the separation is effected in the partial separation or rectifying zones 101 of Fig. 2 or 30 of Fig. 1 may be varied over quite a wide range, preferably between temperatures of, say, 140 degrees F., more or less, and 300 to 325 degrees F. more or less. These temperatures are given for an operation at atmospheric pressure and if pressure is employed, the temperatures just given will have to be raised to correspond with the increase in boiling points of the hydrocarbons, due to the increase in pressure.

The partial condensation or rectification zone 30 or 101 and rectifying zone 41 or 111 of Figs. 1 and 2, respectively, may be maintained at substantially atmospheric pressure or superatmospheric pressures, and if it is desired to maintain either one or both of these zones under a pressure higher than that pre-

vailing on the vapors entering said zone, vapor pumps or compressors may be interposed on the lines in order to maintain the desired pressures.

5 As an illustration, this operation may be carried out in connection with a process where hydrocarbon oils are cracked under high temperatures and pressures by being passed through heating coil 4 and being raised 10 therein to a temperature of approximately 900 degrees F., more or less under a pressure which may be, say, approximately 500 pounds, said pressure being reduced by means of valve 6 to approximately 80 pounds on chamber 7. 15 The conditions of time element in said coil and chamber may be such that under the temperatures and pressures used therein, the residuum withdrawn from chamber 7 through line 8 contains less than 5% and preferably less than 2% sludge as measured by benzol 20 centrifuge. The dephlegmating and rectifying zones connected to chamber 7, as heretofore described, may be maintained substantially under the same pressure as chamber 7 25 or under a lower pressure. By the use of vapor pumps shown, or by the interposition of vapor pumps (not shown) at proper points, as well as by the use of the valves shown on the various lines, any suitable decreasing or increasing differential pressures 30 may be maintained, if desired, on the various parts of the process between dephlegmating zone 13 and the final rectifying or stabilizing zone 41 or 111.

35 The process may also be carried out under such conditions as will cause so-called vapor phase cracking, or it may be so operated that while cracking takes place in the operation, it is a secondary object thereof.

40 Depending upon the purpose of the operation and whether cracking is a primary or secondary object thereof, the reflux condensate from the dephlegmator 13 or, when a series of dephlegmating zones is utilized, one or 45 more streams of reflux condensate, may be returned to the heating tubes for retreatment; or no reflux condensate may be permitted to return to the heating zone for retreatment, the stream or streams being then 50 sent to storage or separate treatment. Further, dependent upon the same factors, the temperatures and pressures utilized in the process will be varied, the temperatures and pressures given above in the operations 55 illustrated being in no way limitative of the scope of the processes in which the features of this invention may be utilized.

60 The partial condensing, rectifying, and gas separating phase of this invention has particular utility and advantage of adaptation when it is used for treating oil in connection with a process of the so-called tube and tank type, wherein a large differential in pressure is maintained between the heating coil or tube and the enlarged tank, whether crack-

ing is the primary or a secondary object of the treatment. In such process the differential in pressure is most advantageous to the production of comparatively large yields of motor fuels with a minimum comparative 70 formation of coke and sludge. On the other hand, it inherently tends to increase the loss of fractions of these motor fuels with the gases. This latter disadvantage can only be balanced by providing in combination with 75 the heating and reacting part of the process, costly and intricate rectifying apparatus, which, according to the methods heretofore used in their operation, did not provide for the overall advantages and efficiency of the 80 present invention.

I claim as my invention:

1. A method for treating the vaporous and gaseous mixture produced in the cracking of hydrocarbon oils which comprises dephlegmating the mixture of vapors and gases to condense and separate therefrom fractions heavier than gasoline, then subjecting the mixture to partial condensation at a temperature above atmospheric to condense therefrom a heavy gasoline cut while retaining a lighter gasoline cut in vapor form, separating the condensed heavy gasoline cut from the vapor-gas mixture, and then rectifying the mixture in the absence of said condensed heavy gasoline cut to sharply separate and condense said lighter gasoline cut from the incondensable gases. 90

2. A method for treating the vaporous and gaseous mixture produced in the cracking of hydrocarbon oils which comprises dephlegmating the mixture of vapors and gases to condense and separate therefrom fractions heavier than gasoline, then subjecting the mixture to partial condensation at a temperature above atmospheric, to condense therefrom a heavy gasoline cut while retaining a lighter gasoline cut in vapor form, separating the condensed heavy gasoline cut from the vapor-gas mixture, in introducing the mixture to the lower portion of a rectifying column which is heated at the bottom and cooled at the top and wherein the vapors and gases rise countercurrent to descending condensate formed therein, and rectifying the mixture in said column in the absence of said condensed heavy gasoline cut to sharply separate and condense said lighter gasoline cut from the incondensable gases. 110

3. A method for treating the vaporous and gaseous mixture produced in the cracking of hydrocarbon oils which comprises dephlegmating the mixture of vapors and gases to condense and separate therefrom fractions heavier than gasoline, subjecting the mixture to partial condensation in a manner to condense therefrom the gasoline hydrocarbons boiling above approximately 200° F. at atmospheric pressure, while retaining in vapor form the gasoline hydrocarbons boiling be- 120

low approximately 200° F. at atmospheric pressure, separating the resultant gasoline condensate from the vapor-gas mixture, and then rectifying the mixture in the absence of said condensate in a manner to condense said gasoline hydrocarbons boiling below approximately 200° F. and to sharply separate the same from the incondensable gases.

said gasoline hydrocarbons boiling below approximately 200° F. and to sharply separate the same from the incondensable gases, and blending the thus separated and condensed gasoline hydrocarbons with said resultant gasoline condensate.

In testimony whereof I affix my signature.
JEAN D. SEGUY.

75

4. A method for treating the vaporous and gaseous mixture produced in the cracking of hydrocarbon oils which comprises dephlegmating the mixture of vapors and gases to condense and separate therefrom fractions heavier than gasoline, then subjecting the mixture to partial condensation at a temperature above atmospheric to condense therefrom a heavy gasoline cut while retaining a lighter gasoline cut in vapor form, separating the condensed heavy gasoline cut from the vapor-gas mixture, and then rectifying the mixture in the absence of said condensed heavy gasoline cut to sharply separate and condense said lighter gasoline cut from the incondensable gases, and blending the condensed lighter gasoline cut with said condensed heavy gasoline cut.

80

5. A method for treating the vaporous and gaseous mixture produced in the cracking of hydrocarbon oils which comprises dephlegmating the mixture of vapors and gases to condense and separate therefrom fractions heavier than gasoline, then subjecting the mixture to partial condensation at a temperature above atmospheric, to condense therefrom a heavy gasoline cut while retaining a lighter gasoline cut in vapor form, separating the condensed heavy gasoline cut from the vapor-gas mixture, in introducing the mixture to the lower portion of a rectifying column which is heated at the bottom and cooled at the top and wherein the vapors and gases rise countercurrent to descending condensate formed therein, and rectifying the mixture in said column in the absence of said condensed heavy gasoline cut to sharply separate and condense said lighter gasoline cut from the incondensable gases, and blending the condensed lighter gasoline cut with said condensed heavy gasoline cut.

6. A method for treating the vaporous and gaseous mixture produced in the cracking of hydrocarbon oils which comprises dephlegmating the mixture of vapors and gases to condense and separate therefrom fractions heavier than gasoline, subjecting the mixture to partial condensation in a manner to condense therefrom the gasoline hydrocarbons boiling above approximately 200° F. at atmospheric pressure, while retaining in vapor form the gasoline hydrocarbons boiling below approximately 200° F. at atmospheric pressure, separating the resultant gasoline condensate from the vapor-gas mixture, and then rectifying the mixture in the absence of said condensate in a manner to condense
